UNITED STATES PATENT OFFICE

THOMAS W. STONE, OF FORT WAYNE, INDIANA, ASSIGNOR TO THE WESTERN GAS CONSTRUCTION COMPANY, OF FORT WAYNE, INDIANA, A CORPORATION OF INDIANA

WATER-GAS PROCESS

Application filed November 22, 1923. Serial No. 676,308.

The invention relates to a method of producing water gas and more particularly to a method of producing water gas involving the reverse steam-flow principle, and has 5 for its objects to employ the reverse steam-flow principle for the production of water gas during both the "up" and "down" runs through the generator, whereby regeneratively superheated steam may be employed 10 in the entire operation of gas production.

According to present practice involving the use of the reverse steam-flow principle, the procedure has been to preheat the steam only on the reverse steam-flow and during 15 the "down" run in the generator as distinguished from the "up" run. In the present invention the process is designed to effect a preheating of the steam during both the "down" run and the "up" run through the 20 generator, with results that the process will be more complete, better balanced, and more efficient, than in former processes employing the reverse steam-flow principle.

By the invention, there results a more 25 complete dissipation of the products in the apparatus, a more efficient and complete production of gas, because the injection of hydrocarbon oils into the apparatus is permitted during the "down" run as well as 30 during the "up" run, both of which also involve employment of the regenerative action of the reverse steam-flow.

In addition to the general objects recited 35 above the invention includes among its objects such other improvements and advantages in construction and operation as are found to obtain in the structure and devices hereinafter described or claimed.

In the accompanying drawings, forming a 40 part of this specification, and showing, for purposes of exemplification, a preferred form and manner in which the invention may be embodied and practiced, but without limiting the claimed invention specifically to such illustrated instance or instances:

Fig. 1 is a side elevation diagrammatic in 45 character of a water gas apparatus or set involving the present invention.

Fig. 2 is a plan view of the same, also generally diagrammatic in character.

Referring to the drawings, 1 indicates a generator of any desired or preferred type as is commonly used in water gas manufacture and which is charged with fuel from a charging opening or feeder located at the top thereof and indicated at 1^a; 2, the carbureter, and 3 represents the superheater. Communication between the upper portion 55 of the fuel chamber of the generator and the carbureter is provided by symmetrically located substantially horizontal pipes 4 and 5 having branch pipes 6 and 7 communicating with the upper portion of the carbureter. A hot valve 10 is provided in the pipe 4 as is usual in water gas sets of the general character illustrated, the hot valve controlling the alternate "up" and "down" runs through the generator, during the gas producing 60 cycle. In its "down" position the hot valve 10 cuts off communication between the pipe connection 27 leading to the generator, and the carbureter 2 through the lower pipe connection 36, and in this position of the hot valve the blast is ready to be turned on, the upper connection 4 between the generator and the carbureter being open to permit blast products to pass from the upper portion 65 of the generator into the carbureter. In its "up" position the hot valve cuts off communication between the generator and the carbureter through the pipe connection 4 and establishes communication between these elements through the aforesaid lower 70 connection 36. This latter position of the hot valve is effected at the conclusion of the blast and preparatory to a gas making run.

According to the invention, the carbureter 2 is divided into halves by a fire brick partition wall 11, providing in effect a separate carbureter chamber communicating with each of the pipes 4 and 5 leading to the generator 1. Oil sprays 12 and 13 are located on the top 75 portion of the carbureter 2 and are designed to introduce oil or other suitable enriching hydrocarbons into the carbureter, each spray communicating with one of the carbureter compartments formed by the partition wall 11. The superheater 3 is similarly divided 80

- by a central partition wall 14 into semi-circular halves and communication between the separate compartments of the carbureter and the two chambers or compartments of the superheater is afforded by means of a lower pipe connection 15 divided into two separate compartments by means of a partition wall 16 so that separate continuous passageways will be maintained between and through the carbureter and superheater. Stack valves 17 and 18 are provided, one for each compartment of the superheater 3, said valves being of usual or preferred construction, operated in the ordinary manner, and communicating with a stack or stacks 17^a. Communication between the two compartments of the superheater 3 and a tar seal box 19 is provided by the pipes 20 and 21 having valves 22 and 23 therein which are designed to be hydraulically controlled so that either of said valves may be opened or closed or both may be opened at the same time. The tar seal box 19 is further provided with a riser pipe 24 for the discharge of the water gas.
- From the construction described, it will be seen that two separate and continuous passages are maintained from the generator 1 through the connections 4 and 5 to the carbureter, through the lower connection 15 to and through the separate compartments of the superheater, and then out through the corresponding stack valves 17 and 18 or through the tar seal box connections 20 and 21 to the tar batter and gas main according to whether a blow or run is in progress.
- The air blast is produced by a blower 25 and is conducted to the lower portion of the water gas generator, below the fuel bed by means of a horizontal pipe 26 terminating in a down run pipe 27 and which blast enters the generator below the grate by means of the connection 28 with which the lower end of the down run pipe 27 communicates. A suitable blast control valve 35 of usual construction is located in the pipe 26. Branch pipes 31 and 32 are provided which communicate at one end with the blast pipe 26 and at their other ends communicate with the two chambers of the carbureter.
- Carbureter blast valves 33 and 34 are located in the branch pipes 31 and 32 to control the blast into the carbureter.
- Steam pipes or connections 29 and 30 are provided communicating respectively with the offtake pipes 20 and 21, leading from the superheater, at points between the valves 22 and 23 and the separate chambers of the superheater 3. These steam connections are similar to those ordinarily used in water gas apparatus and are provided with the usual cut-off valves, steam heaters, pressure regulators, and other appurtenances, such as are generally employed.
- The method of operation of the several elements described in order to produce water

gas in accordance with the present invention is as follows: In order to bring the machine or set up to operating temperature the air blast is first introduced into the pipe 26 through the blast valve 35 which is opened, and into the base of the generator through the "down" run connection 27, the hot valve 10 being in its down position to prevent the blast from entering the carbureter prior to its entrance into the generator, and the pipe connection 4 between the carbureter and the top of the generator being open in the position of the hot valve.

From the lower portion of the water-gas generator 1 the blast passes up through the fuel bed and at the top of the generator the blast gases will pass through the pipe connections 4 and 5 into the two parallel compartments of the carbureter. As the blast gases from the generator pass into the two compartments of the carbureter, they will meet an auxiliary air blast introduced into both chambers of the carbureter from the auxiliary connections 31 and 32 and carbureter blast valves 33 and 34, in order to produce a secondary combustion in the two compartments of the carbureter. From the carbureter, the blast gases will pass simultaneously and independently through the divided lower connection 15 to the superheater, upwardly in parallel through the two compartments of the superheater and out through the stack valves 17 and 18. The valves 22 and 23 are closed during this operation to prevent the passage of the blast gases into the tar seal box and gas main. This operation is continued until the apparatus has been raised to the required temperature at which time the air blast is discontinued. The carbureter blast valves 33 and 34 and the main blast valve 35 are then closed and the hot valve 10 is reversed so that on the left hand of the apparatus the "down" run communication 27 will be ready for use for the "up" run through the fuel bed in the generator.

Steam is introduced through the pipe 29 into the lower half of the superheater as viewed in Fig. 2, the valve 22 being closed and the valve 23 being in open position. The steam so admitted will pass downwardly through one side of the superheater, through one section the lower communication 15 to the corresponding compartment of the carbureter, upwardly through this compartment of the carbureter into the carbureter nozzle or branch connection 6, through the hot valve 10 which is open and into the generator through the "down" run connection 27. During this passage through the several elements described, the steam has been highly superheated by its passage through the checkerbrick and is highly superheated when introduced to the water gas generator. The steam so superheated will pass upwardly through the fuel bed, combining with the constituents

thereof and the steam and resulting gases are conducted from the generator through the connections 5 and 7 into the other half or compartment of the carbureter 2. The gaseous products resulting from the passage of the steam through the fuel bed of the generator and which are conducted as described into the other half of the carbureter have been converted into uncarbureted water gas or what is known as blue water gas. As the gas so produced enters the carbureter, oil is introduced by means of the spray 13 and the enriched gaseous products pass downwardly through the carbureter, through the hitherto unused half of the lower connection 15 into the superheater. The gases thence pass upwardly through the right half of the superheater and out through the offtake connection 21 and open valve 23 into the tar seal box 19 and thence through the riser pipe connection 24 into the gas line. The operation described is the making of a standard steam "up" run on a water gas set with the steam superheated or regenerated by one half of the carbureter and superheater checker brick.

The next ensuing operation corresponds to the ordinary steam "down" run, in combination with which the reverse steam-flow is also employed. The valve 22 is opened and the valve 23 is closed. Steam is no longer admitted through the connection 29 but is admitted through the pipe 30 and will pass down to the right or other half of the superheater as viewed in Fig. 2 looking from the generator 1 towards the seal box 19, through the corresponding lower connection to the carbureter, up through the right half of the carbureter and out through the connections 7 and 5 and into the top of the generator, the hot valve 10 being maintained in the same position to connect the bottom of the generator with pipe 4. Superheated steam so admitted is forced downwardly through the fuel bed within the generator and is transformed into blue water gas. From the lower portion of the generator the resultant blue water gas passes upwardly through the "down" run connection 27 and is conducted to the carbureter through the connections 4 and 6 in a similar manner as obtains in present practice for a "down" run. Oil is now admitted to the incoming gas through the oil spray 12 instead of the oil spray 13, and the resultant enriched gases pass down through the left half of the carbureter, through the carbureter superheater connection 15, upwardly through the superheater, outwardly through the offtake pipe or communication 20 into the tar seal box and thence through the riser connection into the gas line. The latter operation described permits of oil being introduced into the gas during the combined down run and reverse steamflow.

After the steam has passed through in the

manner described for the desired or proper length of time, the oil is shut off at the spray 12 and the steam and resultant gases are allowed to flow through the apparatus until all of the vapors have been properly purged out. Steam is then cut off from the pipe 30 and is admitted from the pipe 29 and is passed backwardly through the set in the same direction as during the first operation described, but during this last reversal no oil is admitted into the carbureter from the spray 13. This arrangement provides for steam at the ash pit of the generator so that no blue water gas is left. As soon as this has been accomplished the steam is shut off from the pipe 29 and the valve 23 is closed. The stack valves 17 and 18 are opened together with the blast valve 35. Shortly thereafter the carbureter blast valves 33 and 34 are opened simultaneously, which operation brings the apparatus to the completion of its cycle and the apparatus is again ready to be preheated by means of the air blast from the blower 25 in the manner described.

The invention as hereinbefore set forth is embodied in a particular form of construction but may be variously embodied within the scope of the claims hereinafter made.

What is claimed is:

1. A method of making carburetted water gas which consists in: passing a blast of air vertically upwardly through a fuel bed in a single water gas generator thereby forming air blast gas and passing the air blast gas in independent streams to and burning it in separate compartments of a single shell carbureter and a single shell superheater by admitting secondary air thereto; then discontinuing such passage of air; then passing a flow of steam successively through a compartment of the superheater, a compartment of the carbureter and upwardly through the fuel bed of the generator to make water gas, and passing the water gas from the top of the generator successively through another compartment of the same carbureter and enriching the water gas with oil therein and through another compartment of the same superheater to fix the gas therein; discontinuing such flow of steam and passage of gas and, before again reheating the single generator and the compartments of the single carbureter and superheater, passing a flow of steam successively through the compartments of the superheater and carbureter that were just used for fixing and enriching the water gas and thence downwardly through said fuel bed to make water gas, and passing the water gas from the bottom of the generator successively through the compartments of the carbureter and superheater through which steam was previously passed to the generator and enriching with oil in the carbureter and fixing in the superheater the water gas while flowing therethrough.

2. In making water gas the method which consists in: introducing a blast of air through the fuel bed of a generator to bring the fuel bed to incandescence and to produce 5 air blast gases and passing the air blast gases successively in separate parallel streams through a single shell carburetter and a single shell superheater and burning the air blast gases therein; shutting off said air blast 10 and introducing a flow of steam successively through the superheater, carburetter and incandescent fuel bed of said generator, to generate water gas in said generator, and passing the water gas generated back 15 through said carburetter and superheater to a gas receiver; and, before again introducing a blast of air, then reversing the direction of flow of steam through said elements and introducing a flow of steam successively 20 through the superheater, carburetter and fuel bed of the generator to generate water gas before again bringing the fuel bed to incandescence, and passing the water gas generated back through said carburetter and 25 superheater to a gas receiver.

3. A method as claimed in claim 2, and in which the water gas is enriched with oil in the carburetter and fixed in the superheater during both directions of flow of 30 steam to make carburetted water gas.

4. In making water gas the method which consists in: passing a blast of air vertically through the fuel bed of a single generator to produce air blast gases and thence passing 35 the air blast gases in independent streams through separate compartments of a shell carburetter and a single shell superheater and burning such blast gases in the compartments of the carburetter and superheater by 40 admitting secondary air; shutting off said air blast and then passing steam successively through one superheater compartment and one carburetter compartment and the fuel bed of the generator to make water gas and 45 passing the water gas back through the other carburetter compartment and superheater compartment; then reversing the direction of flow of said steam and then, before again passing a blast of air through said elements, 50 passing steam successively through said other superheater and carburetter compartments to and through the fuel bed in the generator to make water gas, and passing said water gas successively through said one 55 compartment of the carburetter and superheater compartments.

5. A method as claimed in claim 4, and in which the water gas made during both directions of flow of steam is enriched by oil in 60 the respective carburetter compartments and fixed in the respective superheater compartments to form carburetted water gas during both directions of flow of steam and water gas.

6. In the operation of a previously heated

water gas set comprising a single generator, a single shell carburetter and a single shell superheater: the method which consists in passing steam successively through the superheater and carburetter and thence passing the superheated steam vertically through a fuel bed in the generator to make water gas, thence passing the resultant water gas back through independent compartments of the same carburetter and superheater and 70 enriching the gas with oil in the carburetter compartment and fixing the gas in the superheater, and then, before the generator, carburetter and superheater are again heated reversing the flow therethrough and passing steam successively through the compartments of the superheater and carburetter and thence passing the superheated steam vertically through the fuel bed in the generator to make water gas, thence passing the 75 resultant water gas back through the carburetter and superheater and enriching the gas with oil in the carburetter and fixing the gas in the superheater.

THOMAS W. STONE. 90
